SPACE CONDITION RESPONSIVE INSTRUMENT

Henry Dreyfuss, South Pasadena, Calif., assignor to Minneapolis-Honeywell Regulator Company, Minneapolis, Minn., a corporation of Delaware

Application April 25, 1958, Serial No. 50,623

Term of patent 14 years

(Cl. D52—7)

FIG. 1

FIG. 2

FIG. 5

FIG. 3

FIG. 4

Figure 1 is a front view of a space condition responsive instrument showing my new design;

Figure 2 is a rear view of the instrument;

Figure 3 is a side view of the instrument looking from the left side of Figure 1;

Figure 4 is a partial sectional view through the vertical center of the instrument taken along the lines 4—4 of Figure 1; and

Figure 5 is a transverse sectional view taken along lines 5—5 of Figure 1.

I claim:

The ornamental design for a space condition responsive instrument, substantially as shown.
